United States Patent Office

Des. 180,888
Patented Sept. 3, 1957

180,888

ELECTRIC MASSAGER

Rudy Bartell, Berwyn, and Robert B. O'Donnell, Philadelphia, Pa., and Anton J. Schiffer, Chicago, Ill.

Application January 24, 1957, Serial No. 44,586

Term of patent 14 years

(Cl. D83—1)

Fig. 1

Fig. 2

Fig. 3

Fig. 1 is a perspective view of an electric massager embodying our new design;

Fig. 2 is an end elevation of the massager as seen from the right end of the pad as illustrated in Fig. 1; and

Fig. 3 is an end elevation of the massager as seen from the left end of the pad as illustrated in Fig. 1.

We claim:

The ornamental design for an electric massager, as shown.
